UNITED STATES PATENT OFFICE.

PATRICK JOSEPH FLANAGAN, OF NEW ORLEANS, LOUISIANA.

SMOKE-CONSUMING FURNACE.

No. 922,871.

Specification of Letters Patent.

Patented May 25, 1909.

Application filed December 14, 1907. Serial No. 406,404.

To all whom it may concern:

Be it known that I, PATRICK J. FLANAGAN, a citizen of the United States, and a resident of New Orleans, in the parish of Orleans and 5 State of Louisiana, have invented a new and Improved Smoke - Consuming Furnace, of which the following is a full, clear, and exact description.

The object of the invention is to provide a 10 new and improved smoke-consuming furnace, which is simple and durable in construction, and arranged to insure a complete burning of the smoke and gases arising from the burning fuel in the fire box, utilizing the 15 burning fuel to the fullest advantage for heating purposes and providing a complete consumption of the fuel.

The invention consists of novel features 20 and parts and combinations of the same, which will be more fully described herein- 25 after and then pointed out in the claim.

A practical embodiment of the invention is represented in the accompanying drawings forming a part of this specification, in 25 which similar characters of reference indicate corresponding parts in all the views.

Figure 1 is a longitudinal sectional elevation of a boiler furnace provided with the improvement; Fig. 2 is a sectional plan view 30 of the same on the line 2—2 of Fig. 1, and Fig. 3 is a transverse section of the same on the line 3—3 of Fig. 1.

In the brick-work A of the furnace is set in the usual manner the boiler B, below the 35 front end of which is arranged the fire box C having a grate formed of longitudinally extending tubiform grate bars D, supported at their rear ends on the bridge wall E of the furnace. The front ends of the hollow grate 40 bars D are engaged by apertured nipples F' formed on the inner side of a transversely-extending distributing chamber F set in the sides of the brick-work A, as plainly indicated in Fig. 2. One end of the distributing cham- 45 ber F is connected with a discharge pipe G' of a blower G of any approved construction, and having its inlet pipe G² connected with the smoke box H of the boiler furnace, the smoke box being connected in the usual man- 50 ner with the stack I, having a damper or valve J, adapted to be opened or closed by the operator in charge of the furnace.

The top of each grate bar D is provided 55 with perforations D', and the bottom of each grate bar is provided at the rear end with a discharge opening D², for the ashes, cinders

and the like passing into the hollow grate bars D. The discharge openings D² are adapted to be opened and closed by shutters or valves K, secured on a transversely-extending slide K', mounted to slide in suitable bearings K² attached to the bridge wall E, one outer end of the slide K' being connected with a lever L under the control of the operator, for moving the slide K' transversely, 60 with a view to move the shutters K into an open or a closed position relative to the discharge openings D².

When the fuel is burning on the grate bars D and smoke and gases arise and pass 70 through the combustion chamber and through the flues in the boiler B into the smoke box H, then the smoke and gases are prevented from passing into the stack I on account of the damper J being closed, the smoke and 75 gases being drawn from the smoke box H by way of the inlet pipe G² into the blower G, which forces the smoke and gases through the discharge pipe G' into the distributing 80 chamber F, by way of the apertured nipples F', into the hollow grate bars D, from which the smoke and gases are forced up through the openings D' into the burning fuel, to be consumed in the fire box C. Thus 85 by the arrangement described the smoke and gases arising from the burning fuel on the hollow grate bars D are returned by way of the hollow grate bars back into the combustion chamber, to be consumed therein, and when the fuel is burning brightly and 90 the smoke and gases are consumed then the said blower G may be stopped and the damper J opened, to allow running of the furnace with natural draft. Cinders, ashes and like extraneous matter passing through 95 the openings D' into the hollow grate bars D are forced rearward therein by the blast of smoke and gases passing from the distributing chamber F into the hollow grate bars D, the said cinders and ashes being dis- 100 charged through the openings D² into the ash pit C' whenever the operator moves the shutters K into an open position.

The hollow tubular grate bars D may extend at their ends through the bridge wall 105 E, and in this case the discharge openings D² are at the rear ends of the grate bars, to permit of discharging the cinders to the rear of the bridge wall. The openings D² are controlled by shutters or valves K, as 110 above explained. It will also be noticed that the grate bars can be readily replaced

by new ones in case of being burned out or otherwise injured.

By the arrangement described a complete consumption of the smoke and gases arising from the burning fuel in the fire box takes place, and consequently the heat generated is utilized to the fullest advantage, and a complete consumption of the fuel takes place.

10 The smoke-consuming furnace shown and described is very simple and durable in construction and is composed of comparatively few parts, not liable easily to get out of order.

15 Having thus described my invention, I claim as new and desire to secure by Letters Patent:

In a furnace of the class described, a bridge wall a transversely extending air dis-

tributing chamber in the brick work of the 20 furnace at the front thereof, and provided with a plurality of hollow nipples on its inner face, a plurality of hollow grate bars engaging the nipples at their front ends, and supported on the bridge wall at their rear 25 ends, said bars having a plurality of openings in their upper faces and provided with outlet openings at their rear ends on the under sides thereof, and closures for the openings.

30 In testimony whereof I have signed my name to this specification in the presence of two subscribing witnesses.

PATRICK JOSEPH FLANAGAN.
